[57] CLAIM

The ornamental design for a clock, as shown and described.

DESCRIPTION

FIG. 1 is a perspective view of the clock, showing my new design;

FIG. 2 is a front elevational view thereof;

FIG. 3 is a right side elevational view thereof;

FIG. 4 is a left side elevational view thereof;

FIG. 5 is a back elevational view thereof; and,

FIG. 6 is a top plan view thereof.

The broken line showings of a dial and various mechanism parts are for illustrative purposes only and form no part of the claimed design.
